By his Attorney
Albert M. Austin.

UNITED STATES PATENT OFFICE.

WILLIAM H. HOWARD, OF SALT LAKE CITY, UTAH, ASSIGNOR TO AMERICAN SMCING AND REFINING COMPANY, OF NEW YORK, N. Y., A CORPORATION OF NEW JERSEY.

PROCESS OF DISCHARGING SMELTER GASES.

1,422,575.

Specification of Letters Patent. Patented July 11, 1922.

Application filed March 8, 1921. Serial No. 450,756.

To all whom it may concern:

Be it known that I, WILLIAM H. HOWARD, a citizen of the United States, and resident of Salt Lake City, in the county of Salt Lake 5 and State of Utah, have invented certain new and useful Improvements in Processes of Discharging Smelter Gases, of which the following is a specification.

The invention relates in general to an improvement in the method and apparatus for handling obnoxious gases in the act of discharging such gases into the atmospheric air, and specifically relates to an improvement in the method of discharging into the air those gases which are deleterious to vegetable and animal life, such for instance as the sulphur dioxide fumes discharged in certain smelting and other metallurgical operations.

It is well known that considerable difficulty has been experienced in metallurgical plants to insure the discharge of sulphur dioxide and similar fumes in such a way that these gases will be diffused in the upper regions of the atmospheric air and accordingly diluted to such an extent that they will not be harmful should they be forced back to the ground by prevailing atmospheric conditions.

It is understood that these gases come off of the furnaces at extremely high temperatures and it is usual to pass the gases into high chimney stacks but this is not entirely satisfactory and there is, of course, a limit 35 in the height to which these stacks can be built.

One of the objects of the invention is to provide a simple, easily practiced and economical method for discharging obnoxious 40 gases in such a way as will minimize their tendency to damage vegetable and animal life.

The invention contemplates the subjecting of these gases while confined in the usual 45 high chimney stack to such a treatment as will cause them to lose in a large measure their obnoxious characteristics even before they are discharged, and finally to discharge them from the stack in such a way as will 50 cause the column of gas to bore through the atmosphere above the discharge end of the stack and thus confine the gases even in the absence of a continuation of the stack. This columnar form has the effect of holding the 55 gases in a closely projected stream until they

reach a material height above the high stack, and in this way the discharging act tends to increase the possibility of the obnoxious gases being so diluted before they can reach the ground that their obnoxious character 60 will have entirely disappeared.

Broadly, I attain this object by introducing into the stack, adjacent its base, air or some other diluting and unobjectionable gas in a volumetric sufficiency to supply an excessive amount of inoffensive gas capable of mixing with and highly diluting the obnoxious gases, and preferably by so heating these diluting gases to a temperature equal to or even in excess of the temperature of the obnoxious gases, and in maintaining contact between the gases for the whole length of the stack so that all the gases present are discharged at high nozzle velocity and capable of boring through the upper air spaces before the column of gases is diffused in the air.

Considering the apparatus features of the disclosure, an object of the invention is to provide a simple form of instrumentality 80 for effectively and efficiently practicing the above outlined method and in which the chimney element features a discharge nozzle construction to increase the far-reaching effect of the discharged gas column.

Referring to the accompanying drawing which will be utilized in describing one preferred method of practicing the invention, there is shown in diagrammatic outline the discharge stack of a metallurgical furnace equipped with an auxiliary gas heater illustrating a preferred embodiment of the apparatus feature of the disclosure.

In the drawings there is shown diagrammatically at 10 the discharge conduit of a conventional form of smelting furnace which is discharging obnoxious gases, such as sulphur dioxide, into a stack 11. This stack is of conventional form, and while not necessary to the practicing of the invention herein disclosed, is preferably of the high type so as to take advantage of the long heating space provided by such a high stack and to take advantage of the usual high discharge point for the gases. The invention comprises the projective force of the gases in the present disclosure to attain an additional height over the present high point discharges from such chimney stacks.

A supplemental gas heating unit indicated at 12 is disposed adjacent the base of the stack and discharges by means of an upwardly inclined conduit 13 into the base 5 of the stack but it is to be understood that this supplemental heating unit is otherwise independent of the furnace and its stack. In the present disclosure air is passed 10 through the auxiliary heater; is given a high temperature, preferably equal to or higher than the temperature of the obnoxious gases at the base of the stack, and this hot air is discharged directly into the stack preferably in large volume. While it will be 15 found that the natural draft created by the gas heater is sufficient to supply the requisite amount of air and at the proper temperature, it is suggested that the air may be forced under pressure through the heater 20 and into the stack and for this purpose there is illustrated a blower 14 of any conventional form. While reference has been made to the member 12 as an air heater it is to be understood that its products of combustion 25 may be discharged directly into the conduit 13 and thus add to the air discharged.

In operation and assuming that the furnace is functioning as usual, discharging its 30 sulphur dioxide and other obnoxious gases into the tall chimney stack, the air heater is started and, if necessary, the blower is set in operation. The air and products of combustion are quickly and intensely heated 35 and passed into the stack. The hot air is thus brought into intimate contact, mixing with the obnoxious gases and by the time the mixture has reached the top of the stack the gases have been thoroughly diffused 40 one in the other and in this way the obnoxious gases are diluted even before they are discharged from the stack.

Another action is going on during this 45 mixing operation. The heat of the hot air is imparted to the obnoxious gases so that the mixture in the stack may be even at a higher temperature than the obnoxious gases discharged into the bottom of the stack and the result is that the mixture 50 travels at high velocity through and out of the stack.

It has been observed that when leaving 55 the stack the gases maintain their columnar effect and, possibly due to the converging nozzle shape top of the stack, the upper portion of the gas column appears to contract. The effect of this forceful propulsion is to hold the gases together, and they do not spread out immediately after leaving 60 the stack. On the contrary the column of gases rise above the stack in a solid gas stream for several hundred feet in effect boring a hole through the atmospheric layers. Above the constricted portion the gases 65 begin to spread out into a mushroom-effect

and are quietly and slowly dissipated into the air.

It has been found in the vicinity of plants in which this method is practiced that the blighting effect on vegetation heretofore known 70 has practically disappeared, and the objections heretofore present to discharging such obnoxious gases even out of the usual high stack have disappeared. The method is economical for in some plants a suitable 75 source of waste heat is usually available, and in other plants combustible gas is available for the heater, and in any case the only additional cost is in the installation and maintenance of the air heater for supplying 80 the hot diluting air to the stack.

While I have shown and described and have pointed out in the annexed claims, certain novel features of my invention, it will be understood that various omissions, substitutions and changes in the form and details of the device illustrated and in its operation, may be made by those skilled in the art without departing from the spirit of the invention. 90

Having thus described my invention, I claim:

1. In the art of safely discharging into the air, furnace gases which are obnoxious or harmful to vegetation or animal life, the 95 method which consists in discharging such gases into a chimney or similar conduit extending high into the air, and simultaneously discharging into the chimney so as to mix thoroughly with the obnoxious gases 100 therein, a gas of an unobjectionable character having a temperature higher than the temperature of the atmosphere and in a volume sufficient to mix with and thus dilute the obnoxious gases to an extent such that 105 the mixture formed in the chimney will readily diffuse into the atmosphere and by extreme dilution of the obnoxious gases therein have its objectionable characteristics reduced before it can come in contact 110 with vegetation in the vicinity.

2. In the art of safely discharging into the air hot furnace gases having an obnoxious character, the method which consists in causing the hot gases to move upwardly under 115 their inherent draft through a chimney or similar conduit discharging at its upper end into the air and directing into said chimney a current of hot gases of an unobjectionable character, said diluting gases having a temperature not materially less than the temperature of the obnoxious gases so as not to interfere with the draft incidental to the hot obnoxious gases in the chimney. 120

3. In the art of diffusing obnoxious gases 125 into the air in a manner to protect vegetation and the like, the method which consists in causing such gases to be propelled by their inherent expansive force along a conduit discharging into the air, introducing into the 130

conduit a hot gas free of obnoxious characteristics, maintaining the contact for a period of time sufficient to admit of a thorough mixing of the gases before they are discharged into the air, and thus diluting the obnoxious gases, said diluting gas having an amount of heat per unit volume, sufficient in the presence of the adjacent obnoxious gas to maintain its own conductivity without impairing the rate of propulsion inherent in the hot obnoxious gases.

4. In the art of discharging obnoxious gases, the method which includes a two-step diluting treatment, and comprises first, subjecting the obnoxious gases, while confined, to a mixing therewith of other gases capable when combined therewith of minimizing the objectionable effects of the obnoxious gases, and then as the second step, the projecting 20 of the mixture forcefully high into the air and permitting it to spread out in a mushroom shape and thus become diffused in the upper atmosphere.

5. In the art of discharging gases containing sulphur dioxide into the atmosphere, the method which consists in heating the gases as they are discharged into a chimney to form an ascending column whereby they are caused to move rapidly and forcefully up the chimney, introducing hot air into the lower portions of the gas column maintaining contact between the air and gas for a period of time sufficient to permit of a thorough mixing of the two gases and thus insure a complete dilution of the sulphur dioxide gases, said hot air having a temperature not materially less than the temperature of the sulphur dioxide gases whereby the introduction of the diluting air will not im-

pair the discharging efficiency of the hot sulphur dioxide gases.

6. In a device for diffusing obnoxious gases high into the air, the combination of a chimney stack extending into the air, means for heating said gases as they are discharged into the stack, and means independent of said heating means and opening into the lower portion of the stack for supplying a hot diluting gas to the gases in the stack whereby the hot obnoxious gases and the hot diluting gases are caused to mix before the obnoxious gases are discharged into the air.

7. In a device for diffusing obnoxious gases, the combination of a high chimney stack converging towards its discharge end to form a gas-projecting nozzle, means for feeding the obnoxious gases while hot to said stack, and means for feeding other gases while hot to said obnoxious gases to dilute and heat the same, said nozzle acting on the hot gases discharged therefrom to project the same in a relatively closed column high in the air before they begin to disperse.

8. In a metallurgical plant the combination of a high chimney stack for receiving the obnoxious gases delivered from smelting furnaces and the like, a separate gas heating outfit discharging into said stack heated gases capable of commingling with the obnoxious gases in the stack during their passage therethrough and thus insuring the forceful discharge of said gases high in the air.

Signed at Pasadena, in the county of Los Angeles and State of California, this 22 day of February, A. D. 1921.

WILLIAM H. HOWARD.
